Primary Examiner—Robert A. Delehanty*(74) Attorney, Agent, or Firm*—Wood, Phillips, Katz, Clark & Mortimer(57) CLAIM

The ornamental design for a double-bowl sink, as shown and described.

DESCRIPTION

FIG. 1 is a perspective view taken from the top, front, and right side of a double-bowl sink showing my new design; FIG. 2 is a top plan thereof;

FIG. 3 is a front elevation thereof;

FIG. 4 is an elevation of the right side thereof; and,

FIG. 5 is an elevation of the left side thereof.

The undersigned of the sink shown in the accompanying drawings is not ornamental. Broken-line showings of openings for mountings of faucets, spray nozzles, or other fittings are for illustrative purposes only and form no part of my claimed design.
